UNITED STATES PATENT OFFICE.

ALFRED GREGORY ELY, OF NEW YORK, N. Y., ASSIGNOR OF TWO-THIRDS
TO CHARLES CHRISTOPHER ELY AND FREDERICK ELY, OF SAME PLACE.

DESIGN FOR A NASAL TUBE.

SPECIFICATION forming part of Design No. 22,757, dated August 29, 1893.

Application filed July 19, 1893. Serial No. 480,952. Term of patent 14 years.

To all whom it may concern:

Be it known that I, ALFRED GREGORY ELY, a citizen of the United States, residing at New York, in the county of New York and State of New York, have invented and produced a certain new and original Design for Nasal Tubes, of which the following is a full, clear, and exact description.

My design for a nasal tube comprises a bulbous nose-piece, a depending U-shaped loop, and a mouth-piece projecting from the loop at the extremity farthest from the bulbous nose-piece, at an angle of about forty degrees.

15 The accompanying drawing shows my design in side elevation.

a is the bulbous nose-piece, oval in shape, and open at *b*. *c* is the U-shaped loop depending from the bulbous nose-piece, and *d*

is the mouth-piece, projecting at an angle of 20 about forty degrees (40°) from the upper end of the limb of the loop farthest from the nose-piece, and provided with a flaring end *e*.

The device is made tubular in form.

The leading features of the design are the 25 bulbous (oval) nose-piece, the U-shaped loop, and the mouth-piece set at an angle substantially as shown.

What I claim is—

The design for nasal tubes substantially as 30 shown and described.

In testimony whereof I have hereunto set my hand this 18th day of July, A.D. 1893.

ALFRED GREGORY ELY.
